(57) **CLAIM**

The ornamental design for a pouch for medical inhaler, as shown and described.

DESCRIPTION

FIG. 1 is a front elevational view of the pouch for medical inhaler of the present invention;

FIG. 2 is a rear elevational view of the pouch for medical inhaler of FIG. 1;

FIG. 3 is a right side elevational view of the pouch for medical inhaler of FIG. 1;

FIG. 4 is a left side elevational view of the pouch for medical inhaler of FIG. 1;

FIG. 5 is a bottom plan view of the pouch for medical inhaler of FIG. 1; and,

FIG. 6 is a top plan view of the pouch for medical inhaler of FIG. 1.

The broken line showing of a belt in the drawings is for illustrative purposes only and forms no part of the claimed design.

The broken line belt shown broken away to indicate indeterminate length.
